[57] CLAIM

The ornamental design for a carrier for fire hose or the like, as shown and described.

DESCRIPTION

FIG. 1 is a perspective view of a carrier for fire hose or the like showing my new design;

FIG. 2 is a reduced front elevational view thereof;

FIG. 3 is a reduced left side elevational view thereof, the right side being a mirror image;

FIG. 4 is a reduced top plan view thereof;

FIG. 5 is a reduced rear elevational view thereof; and

FIG. 6 is a reduced bottom plan view thereof.

The broken lines in rectangular configurations shown in FIGS. 1 and 2 are understood to represent conventional stitching.

*FIG. 1.*FIG. 2.

FIG. 4.

FIG. 5.

FIG. 3.

FIG. 6.
